(57) **CLAIM**

The ornamental design for a pole for string lights, as shown and described.

DESCRIPTION

FIG. 1 is a perspective view of a pole for string lights, embodying the new design;

FIG. 2 is a bottom plan view thereof;

FIG. 3 is a top plan view thereof;

FIG. 4 is a left side view thereof;

FIG. 5 is a right side view thereof;

FIG. 6 is a front view thereof; and,

FIG. 7 is a rear view thereof.

The broken lines shown in the drawings illustrate portions of the pole for string lights and form no part of the claimed design.

The pole for string lights is shown with a symbolic break in its length. The appearance of any portion of the article between the break lines forms no part of the claimed design.
